FOUNDATION GARMET

Marcel Gingras, St. Foy, Quebec, Canada, assignor to
Dominion Corset Company, Limited, Quebec, Quebec,
Canada

Filed Nov. 2, 1962, Ser. No. 235,013

Claims priority, application Canada Sept. 18, 1962
4 Claims. (Cl. 128—524)

This invention relates to foundation garments and particularly to panty type girdles in which the leg portions of the garment have a maximum freedom of movement relative to the body encircling portion of the garment.

In panty type girdles there has always been a problem in maintaining a high degree of control of the body portion of the garment with maximum freedom of movement of the leg portions. In most garments of this type body restraining structure has always tended to cramp leg movement. On the other hand, should the body restraining structure be lightened to the extent that leg movement is relatively unrestrained, then the body restraining structure loses its effect and the garment fails to perform its main function. The foundation garment hereinafter described combines a high degree of body control with maximum freedom of movement of the legs.

The invention consists essentially in the provision in the front of the garment of three layers of material, the outer and the intermediate layers each having a lateral band of elastic material along their lower edges, the bands of elastic material being disposed at an angle opposite to each other to provide a cross-over effect, with the upper and outer ends of both bands being located at the hip encircling portion of the garment while the lower and outer ends of both bands are attached to the front of the leg portions of the garment. The inner layer of material is cut to the same shape as that of the outer and intermediate layers and has extensions directed downwards and inset into the leg portions of the garment. All three layers of material are bound together by stitching along their top horizontal edge and along their vertical edges and are secured to side panels of elastic material forming with a rear panel the body encircling and leg portions of the garment.

It is an object of the invention to provide a panty type girdle in which the leg portions of the garment have a maximum freedom of movement combined with a maximum of body control.

A further object of the invention is to provide a panty type girdle in which a front panel consists of three layers of material of which the outer and intermediate panels include crossed over bands of elastic material at their lower edges.

A further object of the invention is to engage the ends of the bands of elastic material with the hip engaging portions of the garment at one end and at their opposite ends engaging with the front of the leg portions of the garment for maximum ease of movement of the legs.

These and other objects of the invention will be apparent from the following detailed description and the accompanying drawings in which:

FIG. 1 is a front elevation of the garment partially broken away to show the three layer construction of the front panel.

FIG. 2 is a side elevation mostly in section on the line 2—2 of FIG. 1.

FIG. 3 is a horizontal section of the front panel portion of the garment taken on the line 3—3 of FIG. 1.

Referring to the drawings, the foundation garment 5 is of the panty type having a body encircling portion 6 and leg portions 7.

The front panel 8 of the garment is constructed of three layers of material, an outer layer 9, an intermediate layer

2

10 and an inner layer 11. The outer and intermediate layers 9 and 10 each have a main portion 9a and 10a of generally unstretchable material each bounded at its lower edge by a band of elastic material 12 and 13 set at an angle to each other as shown in FIG. 1 and each stretchable in the direction of the arrows 12a and 13a to provide a cross-over effect and each adapted to ride freely over the other. The inner layer 11 of the front panel 8 is of generally non-stretchable material and in the body encircling portion of the garment it is cut to the same shape as that of the outer and intermediate layers 9 and 10. This inner layer 11 is provided with a pair of extensions 14 and 15 extending down into the leg portions 7 of the garment.

15 The three layers 9, 10 and 11 are bound together by stitching along their top edge 16 and along their vertical edges 17.

The upper edges 18 and 19 of the bands 12 and 13 may be curved as shown in FIG. 1 to provide a greater 20 area of elasticity in the line of the front portions of each leg.

The panel 8 is joined at its edges 17 to the side panels 20 and waist band 21 both of which are stretchable horizontally in the direction of the arrows 22. The side 25 panels 20 extend downwards to form the sides and rear portions of the legs 7 and are joined to the extensions 14 and 15 of the inner layer 11 of the front panel 8 and also to the rear panel 23. Inserts 24 of stretchable material, stretchable in the direction of the arrow 25 complete the 30 circular formation of the leg portions 7 of the garment which may be bound at their lower edge by the stretchable bands 26. The two leg inserts 24 are joined together at their top edges by the crotch piece 27 which in turn is joined at the front to the inner layer 11 of the front panel 35 8 and at the rear to the rear panel 23.

It will be observed from the above description and from the drawings that the three layer construction of the front panel 8 permits the leg portions of the garment to act independent of body control portion of the garment which 40 is inherent in the front and intermediate layers 9 and 10 and particularly in the cross-over arrangement of the bands 12 and 13. The disposition of these cross-over bands 12 and 13 is of particular importance in their relationship to the body encircling portion of the garment and the 45 legs. As will be seen in FIG. 1, taking the outermost band 12, its vertical edge 12b is located at level of the hip embracing portion of the garment while its vertical edge 12c is located on the front of the opposite leg of the 50 garment. Similarly, the vertical edge 13b of the band 13 is located at the hip embracing portion of the garment directly opposite from the edge 12b and the edge 13c is located on the front of the opposite leg from that to which the edge 12c is secured. The vertical spacing of the edges 12b and 13c and the edges 13b and 12c 55 is such as to allow each leg 7 to swing freely without interference from the adjacent and higher up of either of the bands 12 or 13. The lower portion of the bands 12 and 13 adjacent their anchorage to the legs 7 are not restrictive to movement of the legs as their anchorage to a more 60 constricted portion of the garment, at the hip line, is at the side of panel 8 opposite from its anchorage to a leg and therefore the flexibility of the whole length of the bands 12 and 13 serve to allow freedom of movement of the legs, particularly as one band does not interfere with free 65 stretching of the other band.

What I claim is:

1. A foundation garment of the panty girdle type, the said girdle having a front panel, a pair of side panels, a rear panel and a pair of legs, the said front panel having an 70 inner layer of material, an intermediate layer and an outer layer, the said side panels extending downwards the full length of the garment and forming side portions of the

garment legs, the said inner layer of the front panel having a pair of downwardly extending portions forming the front portions of the said legs, the said inner layer of the front panel including the extended portions being connected along their vertical edges to adjacent edges of the said side panels, the said intermediate and outer layers of the front panel extending in a downwards direction to approximately the top of the said legs and having their lower horizontal edges cut at an angle to the horizontal in a direction opposite to each other, the vertically disposed edges of the said intermediate and outer layers together with said inner layer making a common joint with the said side panels, and a band of elastic material secured to the lower horizontal edges of each of the said intermediate and outer layers of the front panel and secured at their vertical edges to the adjacent edges of the said side panels, the said bands being disposed at an angle to the horizontal and stretchable lengthwise in a direction opposite to each other, one end of each of said bands being located at the hip line of the garment at opposite sides of the front panel and having their opposite ends located at the front portion of the legs of the garment, the said legs of the garment being free to move independently of the said intermediate and outer layers of the front panel and their attached bands.

25

2. A foundation garment as set forth in claim 1 in which the said bands have their vertical depth increased in the area coincident with the front centre line of each of the said legs.

3. A foundation garment as set forth in claim 1 in which the said side panels are formed from material stretchable in a horizontal direction and subject to the pull of the said bands of the front panel.

4. A foundation garment as set forth in claim 1 in which the legs of the said garment are formed by extended portions of the said side and rear panels and of the inner layer of the front panel, and a pair of inwardly facing inserts complete the circular formation of the said legs, the said inserts being joined together to form the crotch of the garment.
